UNITED STATES PATENT OFFICE.

JOHN M. ORR, OF LEESBURG, VIRGINIA.

IMPROVEMENT IN RAILWAY RAIL-CHAIRS AND JOINTS.

Specification forming part of Letters Patent No. 104,057, dated June 7, 1870.

To all whom it may concern:

Be it known that I, JOHN M. ORR, of Leesburg, in the county of Loudoun and State of Virginia, have invented certain Improvements in Railway Chairs and Joints, of which the following is a specification, reference being had to the accompanying drawings.

My invention relates to railways; and it consists in a novel construction and arrangement of the chair, fish-bar, and rail, as hereinafter explained.

Figure 1 is a top plan view of the parts complete and in position. Fig. 2 is a cross-section of the same on the line xx of Fig. 1, with a portion of a car-wheel resting thereon. Figs. 3, 4, 5, and 6 are perspective views of the chair and fish-bar detached.

In making my improved railway-joint I first construct a chair, C, with a lip, I, on one side of proper size and form to fit over the flange of the rail on that side, as shown in the left in Fig. 2, there being a lip or flange, T, on the opposite side, which has its inner face vertical, with a longitudinal inwardly-projecting rib, n, as shown in Figs. 2 and 3. I then construct a fish or joint bar, F, in the form shown in Figs. 4, 5, and 6. This bar has a longitudinal recess, e, along its outer face, corresponding with the rib n on the inner face of the flange T of the chair, as represented in the drawings, this bar F having its opposite side made of a form corresponding to the side of the rail, it having a projection, c, to fit into the cavity between the head and flange of the rail, as shown in Fig. 2. This bar F is slightly rounded on its face at each end, and is made of such a width that when placed in the chair alongside of the rails its upper surface shall come flush with or slightly above the top of the rails, so as to form a bearing for the wheels W as the latter pass over it. As the wheels are made slightly conical, with their smaller ends outward, the bar should be just enough higher than the rails to compensate for this conical form of the wheels, and it may be made very slightly convex on its upper surface, so that when the wheel arrives at its center and directly opposite the joint in the rails the weight shall be borne almost entirely on the bar F, and thus prevent the battering or wearing of the rails at their ends. This bar

F is formed with a couple of projections or shoulders, h, one at each end, far enough apart to permit them to project down over the ends of the chair C when inserted therein, which thus prevent the bar from being moved endwise after being inserted; or, instead of these shoulders h hooking over the ends of the chair, they may have a single projection at the center, as represented by the dotted lines at o, Fig. 6, to fit into a corresponding recess made in the chair, the object and result being the same in either case.

With the parts thus constructed, the chair C is first placed on the sleeper. The bar F is then placed on the chair and shoved outward against the flange T, the rib n entering the recess e in the bar. The rails are then driven or forced in endwise between the lip I and the bar F, as shown in Figs. 1 and 2.

If desired, the ordinary bolts may be used to unite the rails R and the bar F, as represented at a, Fig. 1; but as the rails and bar are both securely locked in the chair in such a manner that neither can be removed except by moving the rail endwise, the bolts may be dispensed with, which will greatly lessen the expense and also the labor of laying the track.

By these means I produce a very strong and durable joint, and lock the rail in the chair in such a manner that it cannot be turned over or wrenched loose, and the chair, being very wide, has a large bearing-surface on the sleeper, and can be spiked down and held very securely in place.

Having thus described my invention, what I claim is—

1. The joint-bar F, provided with the shoulders h, or their equivalents, to hold the same in the chair, substantially as described.
2. The joint-bar F, provided with the shoulders h and longitudinal groove e, in combination with the chair T, having its lip provided with the inwardly-projecting rib n, when constructed and arranged to operate in connection with the rail R, as and for the purpose set forth.

JNO. M. ORR.
